PORHOLE TO LOUVER CONVERTER

Filed April 6, 1949

FIG. 1.

FIG. 4.

FIG. 2.

FIG. 5.

FIG. 3.

INVENTOR,
JOSEPH M. KLINE,
By *Albert A. Mintern*,
ATTORNEY.

tions 14 and 15 snap over the edge 17 of the porthole inner rim 22. The screw 16 is then tightened until the louver head 10 is snugly secured over the porthole 20. The structure is normally installed on a vehicle with the louver head opening 27 facing the rear of the vehicle, as in this position the streamlined shape of the vehicle is preserved and the ejecting action of the head 10 is secured when the automobile is under way.

While I have herein shown and described my invention in one particular form it is obvious that structural changes may be made without departing from the spirit of the invention, such as in the position of the screw on the louver head, the number and shape of the spring arms, and the various proportions of the parts, and therefore I do not desire to be limited to that precise form beyond the limitations which may be imposed by the following claims.

I claim:

1. For mounting over a porthole presented as an opening in the end of a cylindrical sleeve having an externally presented surrounding rim, and a resilient hose telescoped over and extending from the sleeve, an ejector head formed to seat snugly over said rim to center the head; a hood rising from one side of the head to terminate beyond the mid-portion of the head and short of the other side; a planar surface extending beyond the termination of the hood; a screw revolvably extending through said surface; a leaf spring having a length substantially parallel to said surface and screw-threadedly receiving said screw therethrough; a leg of said spring extending from one end of said spring length parallel and in close proximity to the wall of said sleeve; a foot on the end of said leg outturned to engage under the end of said sleeve; a second leg of said spring extending diagonally from the other end of said spring length and from said head within said sleeve; and a foot on said second leg outturned to engage under the end of said sleeve diametrically across from the foot of said first leg; the distance from outside to outside

of said feet being normally greater than the internal diameter of the sleeve.

2. For mounting over a porthole presented as an opening in the end of a cylindrical sleeve having an externally presented surrounding rim, and a resilient hose telescoped over and extending from the sleeve, an ejector head formed to seat snugly over said rim to center the head; a hood rising from one side of the head to terminate beyond the mid-portion of the head and short of the other side; a planar surface extending beyond the termination of the hood; a screw revolvably extending through said surface; a leaf spring having a length substantially parallel to said surface and screw-threadedly receiving said screw therethrough; a leg of said spring extending from one end of said spring length parallel and in close proximity to the wall of said sleeve; a foot on the end of said leg outturned to engage under the end of said sleeve; a second leg of said spring extending diagonally from the other end of said spring length and from said head within said sleeve; and a foot on said second leg outturned to engage under the end of said sleeve diametrically across from the foot of said first leg; the distance from outside to outside of said feet being normally greater than the internal diameter of the sleeve; said spring being rectilinear in cross-section, and said feet having corners engaging said hose to prevent slippage of said feet circumferentially of the sleeve.

JOSEPH M. KLINE.
